PARTITION STRIP ARRESTER APPARATUS
 Clarence A. Heyne, Toledo, Ohio, assignor to Owens-
 Illinois Glass Company, a corporation of Ohio
 Filed Mar. 2, 1960, Ser. No. 12,386
 4 Claims. (Cl. 214—1)

This invention relates to a partition arrester apparatus and more particularly to partition arrester apparatus for use in conjunction with partition sawing apparatus of the type described in U.S. Patent No. 2,855,009, issued to F. A. McCormick.

The partition saw, mentioned above, is designed to automatically cut a bundle of paperboard partition strips into shorter lengths. A résumé of its operation is as follows: A bundle of strips is fed longitudinally into the machine until the bundle reaches a gauge rail. The bundle is clamped and moved transversely through the path of a band saw which severs the forward end of the bundle, i.e., the end between the gauge rail and band saw, into strips of the proper length. The bundle is then returned to its former position and again moved longitudinally against the gauge rail, preparatory for the next cut. These operations are sequentially repeated until the portion which is clamped is too small to be cut to the proper length. This portion then falls through a cut-out in the worktable as scrap.

There are two problems encountered in the operation of this machine. One arises principally in high speed operation of the machine wherein the partition strips bounce when they strike the gauge rail. This results in misalignment of the end edges of the strips or may result in improper gauge, variance in the gauge, etc. of the length of strip desired to be cut; and accordingly, when the bundle is severed the resulting partition strips are of non-uniform lengths. The second problem arises when the last group of strips in a bundle is cut. On the last cut the clamping device, which then clamps the tail end of a bundle, compresses the trailing end edges causing the unclamped leading edges to fan out or become spaced apart. This results in strips becoming cocked in the channel of flow and causes problems in regard to subsequent operations.

My invention relates primarily to a spring-loaded bar having a forwardly inclined knife edge which rides on the top edges of the forwardly moving partition strips and engages backwardly moving partitions, thereby preventing partitions which have struck the gauge rail from bouncing away, and preventing the leading end edges of the strips from moving backward in an arcuate path, i.e., fanning out.

Accordingly, it is an object of this invention to provide apparatus for permitting the forward movement of strips of sheet-like material and restraining the backward movement of strips of sheet-like material, wherein both of said movements are along the same definite path of travel.

Another object of this invention is to provide apparatus for restraining partition strips against backward movement after striking a stationary stop.

Still another object of this invention is the provision of apparatus for preventing the leading end edges of a bundle of partition strips from fanning out when they are gripped near their trailing edges.

A still further object of my invention is to provide an inexpensive attachment for improving the uniformity of strips cut to length in a partition sawing apparatus.

The specific nature of this invention, as well as other objects and advantages thereof, will become apparent to those skilled in the art from the following detailed description taken in conjunction with the annexed sheets

2

of drawings, on which, by way of example only, the preferred embodiment of this invention is illustrated.

In the drawings:

FIG. 1 is a plan view of the apparatus incorporating my invention mounted on a partition saw of the type described in U.S. Patent No. 2,855,009;

FIG. 2 is a vertical sectional view on line 2—2 of FIG. 1;

FIG. 3 is a horizontal sectional view on line 3—3 of FIG. 2; and,

FIG. 4 is a vertical sectional view on line 4—4 of FIG. 3.

Referring to FIG. 1, the partition arrester of my invention is shown mounted on the gauge rail 76 of a partition sawing apparatus as disclosed in U.S. Patent No. 2,855,009, issued to F. A. McCormick.

Basically, the partition sawing apparatus of the above-mentioned patent comprises, in part, a table 70, and clamping means 71, which is mounted on guide rails 72 and moved longitudinally of the table by connecting rod 73 and air cylinder 74, for clamping and moving a bundle of paperboard partition strips 75 longitudinally of the table against a gauge rail 76. After the clamping means 71 releases the bundle 75, the bundle is then gripped and moved transversely of the table into the path of the band saws 77 (by apparatus not shown herein). Strips 79, which have been cut to length, pass between the aforementioned gauge rail 76 and a second parallel gauge rail 78.

Referring now to FIGS. 2—4, and more particularly to my invention, the gauge rail 76, which has a horizontal base portion, is secured to the table 70 by means of fasteners 11. Spaced vertically above the base portion and welded to the gauge rail 76 is a horizontal trapezoidal-shaped support plate 12 (FIG. 3), which supports the operating parts of my invention. Two vertically extending bracket members 14 and 15 are secured by means of screws 13 to one free edge of the support plate. These bracket members have at their upper ends horizontal flanges 16 and 17 which extend over the support plate 12 (FIG. 2). These flanges 16 and 17 have vertical holes 18 and 19 (FIG. 3), which support the upper ends of two guide rods 20 and 21. The rods are secured to the flanges by means of press-fitted pins 22.

The guide rods 20 and 21 extend vertically downwardly from the flanges 16 and 17 and through spaced holes 23 provided in the support plate 12 (FIG. 4). The lower ends of these guide rods are secured to the support plate by means of press-fitted pins 25.

Straddling and secured to the bracket members 14 and 15 by means of screws 26 is a crossarm 27. Intermediate the integral end flanges 28 of the crossarm 27 is a vertical journal bearing 29. This journal 29 has the diametrically reduced non-threaded portion 31 of a screw 30 extending upwardly therethrough. The upper end of this screw is rigidly and non-rotatably secured to the lower collar portion 32 of a manually operated hand-wheel 36 by means of a pin 33. The collar portion 32, which rests on the upper surface of the crossarm 27, maintains the screw in fixed elevation and rotatable relationship on the crossarm.

That portion of the screw 30 which depends from the crossarm is threaded with matching female threads 37a of a carrier 37, which is located intermediate the support plate 12 and the bracket flanges 16 and 17. The carrier has two horizontally spaced apart guide holes 38 (FIG. 4) through which the guide rods 20 and 21 extend, thereby preventing rotation of the carrier relative to the support plate 12 and the gauge rail 76. The screw, and its support structure, and the carrier provide

a supporting platform which is vertically adjustable relative to the table 70.

The center portion of the carrier 37 supports a limit switch L1, which corresponds to the limit switch L1 of U.S. Patent No. 2,855,009. Located between the gauge rail 76 and the two guide holes 38 are provided, as an integral part of the carrier 37, two pairs of clevis-like vertical flanges 40. The vertical flanges 40 have horizontal holes 42 which carry hinge pins 43. When the carrier is at its lowermost position, as shown on FIGS. 10 5 and 3, the flanges 40 extend through cut-outs 56 in the support plate 12.

Pivotedly mounted on the hinge pins 43 are two L-shaped arms 60 each having vertical and horizontal portions, the latter portions extending through cut-outs 50 in the gauge rail when the carrier is adjusted to its lowermost position. The arms 60 may be raised to overlie the gauge rail 76. In the present invention, the arms 60 may be so constructed with relation to the gauge rail 76 that the desired flexibility of adjustment of the arrester may be obtained. This adjustment is accomplished in the present embodiment of the invention through operation of the handscrew 30 on the carriage 37, as described above. Located at the lower ends of the vertical portions are pivot bearings 44 which are mounted on hinge pins 43. Intermediate the ends of the L-shaped arms are slots 45 in which the upper ends of extension springs 46 or similar resilient means as an air spring, dash-pot, etc. are secured as at the pins 47. The lower ends of the springs are secured by means of pins 49 to plates 41 integral with the sides of the flanges 40. These plates 41 also serve to limit the clockwise rotational movement (FIGS. 2 and 4) of the arms 60. The pivotal arms 60, and their associated springs, provide spring-loaded support means for the structure which is to be described hereafter.

Welded to the free ends of the arms 60 and located parallel to the gauge rail 76 are barb-like means. The barb-like means comprise a bar 51 having at its lower end a forwardly inclined surface 52 which in turn has at its lower end a knife-like edge 53. The upper end of the bar 51 is connected by means of an adjustable rod 55 to the limit switch L1.

In operation, the handwheel 36 is rotated to vertically adjust the carrier 37 and hence the inclined surface 52 so that the inclined surface 52 will lie partly in the path of travel of the top edges of the corrugated strips 75. Forwardly moving strips will strike the inclined surface 52 of the bar 51 thereby rotating the bar and the arm about the hinge pin 43 in a counterclockwise direction (FIGS. 2 and 4) and against the extension springs 46. The upward and backward movement of the bar 51 will close the limit switch L1 which is connected thereto by means of the adjustable rod 55. The function performed by the limit switch L1 is disclosed in U.S. Patent No. 2,855,009. The spring tension provided by springs 46 and applied to the supporting arms 60 will assist in keeping the knife edge 53 in contact with the top edges of the strips. This will cause the edge 53 to tend to bite into the bundle of strips 75.

As the strips are brought against and strike the gauge rail 76 they will tend to bounce backwardly. In so doing, they will move against the knife edge 53, which, because of its inclination and because of the downward urging of the springs, will function in the same manner as a barb and engage the strips, thereby preventing backward movement of the strips. The strips may be easily removed without raising the knife edge by moving them transversely of the table and parallel to the gauge rail. As may be seen on FIG. 1, when the bundles are moved transversely on the table between guide rails 76 and 78, the strips slide out from under the

knife edge of the bar 51 after the saw 77 has performed the cutting operation. Thus, the bundle of strips is arrested and maintained by the invention until after cutting to assure uniformity of length of the strips as they are cut to the shorter lengths.

It will, of course, be understood that various details of construction may be modified through a wide range without departing from the principles of this invention, and it is not, therefore, the purpose to limit the patent granted hereon otherwise than necessitated by the scope of the appended claims.

I claim:

1. In apparatus having means for frictionally engaging and advancing a bundle of strips of sheet material on edge in a forward direction against a stationary guide panel and means for moving said bundle transversely after it has come to rest at said guide panel, the improvement comprising: an arrester bar positioned generally parallel to and spaced from said panel, said bar having a downwardly and forwardly inclined surface positioned to contact the top edges of said forwardly moving strips, said surface terminating at its lower end in an edge adapted to engage backwardly moving strips, and means for resiliently supporting said arrester bar in said position, whereby a forwardly moving bundle of strips will engage said inclined surface, raise the bar against said resilient supporting means and move past the bar to the stationary panel, and whereby strips tending to move backwardly after striking said panel will be restrained by the engagement of said edge with such strips.

2. The improvement defined in claim 1, and a limit switch operatively connected to the means for moving said bundle transversely, and means for operatively connecting said switch to said bar whereby the raising of said bar will actuate said switch.

3. Apparatus for uniformly arresting the movement of a bundle of partition strips that are moved forwardly on edge by means that frictionally engage and advance said bundle, comprising, a stationary guide panel positioned transversely to the path of said strips, said panel arranged to halt the forward progress of said strips, an arrester bar positioned generally parallel to and spaced from said panel, said bar having a downwardly and forwardly inclined surface positioned to contact the top edges of said forwardly moving strips, said surface terminating at its lower end in a forwardly inclined knife-like edge, said edge extending across the width of said bundle, and means for resiliently supporting said arrester bar in said position, whereby forwardly moving strips will strike the forwardly inclined surface, raise the bar against said resilient supporting means and move past the bar to the stationary panel, and whereby strips tending to move backwardly after striking said panel will be restrained by the engagement of said knife-like edge with such strips.

4. Apparatus as defined in claim 3, wherein said means comprise means for movably supporting said arrester bar in said position so that said bar is restrained against downward movement but is free to move upwardly out of the path of a forwardly moving bundle, and means for resiliently restraining upward movement of said bar.
